Primary Examiner — Rashida Johnson(74) *Attorney, Agent, or Firm* — Faegre Baker Daniels LLP**CLAIM**

(57) The ornamental design for a handheld musical practice device, as shown and described.

DESCRIPTION

FIG. 1 is a top perspective view of a handheld musical practice device showing my new design;

FIG. 2 is a top view thereof;

FIG. 3 is a bottom view thereof;

FIG. 4 is a right side view thereof;

FIG. 5 is a left side view thereof;

FIG. 6 is a rear view thereof; and,

FIG. 7 is a front view thereof.

The broken lines represent portions of the handheld musical practice device that form no part of the claimed design.

1 Claim, 6 Drawing Sheets# US D723,098 S
